UNITED STATES PATENT OFFICE.

WILLIAM T. CARNES, OF HARMONSBURG, PENNSYLVANIA, ASSIGNOR OF
ONE-FOURTH TO AZRO H. PETTIT, OF CONNEAUTVILLE, PENNSYLVANIA.

ARTIFICIAL LIMB.

SPECIFICATION forming part of Letters Patent No. 760,102, dated May 17, 1904.

Application filed September 23, 1903. Serial No. 174,288. (No model.)

To all whom it may concern:

Be it known that I, WILLIAM T. CARNES, a citizen of the United States, residing at Harmonburg, in the county of Crawford and State of Pennsylvania, have invented certain new and useful Improvements in Artificial Limbs; and I do hereby declare the following to be a full, clear, and exact description of the invention, such as will enable others skilled in the art to which it appertains to make and use the same, reference being had to the accompanying drawings, and to the characters of reference marked thereon, forming part of this specification.

My invention relates to artificial limbs, and has for its object the construction of an artificial hand provided with mechanism so constructed and combined that the fingers of the hand can be operated either with or without the assistance of the wearer's other hand and with the joints of the wrist and fingers so made that they present no shoulders or corners visible through a glove worn on said hand and also with a wrist-joint so adjustable that it can be rotated on its axis and be secured at any desired point to which it may be rotated. These and other features of my invention are hereinafter set forth and described, and illustrated in the accompanying drawings, in which—

Figure 1 is a top or plan view of an artificial arm and a hand embodying my invention. Fig. 2 is a side view of the same. Fig. 3 is an enlarged top or plan view of an artificial hand embodying my invention with parts thereof broken away, showing a part of the mechanism therein. Fig. 4 is a sectional view of the same on the line $\alpha\alpha$ in Fig. 3 looking in the direction of the arrow. Fig. 5 is a sectional view of the same on the line $\gamma\gamma$ in Fig. 3 looking in the direction of the arrow. Fig. 6 is a transverse section of the same on the line $\varepsilon\varepsilon$ through the wrist portion in Fig. 4 looking in the direction of the arrow.

In the drawings, A and A' represent portions of an artificial arm, and B represents an artificial hand. In Figs. 1 and 2 a cord a is shown, which is for the purpose of operating the elbow-joint of the artificial arm. There is also a cord b , by means of which the mech-

anism in the artificial hand is operated. This cord b may have tension applied thereto in any suitable manner; but I prefer to so secure it to the body of the wearer that tension may be applied to it by a slight movement of the shoulder to which the artificial arm is secured. The cord b is attached to a link b' , (see Figs. 3 and 4,) which link b' is pivoted to a lever b'' and which in turn is secured by a pivot b''' in a chamber in the wrist or body of the hand B, as shown in Fig. 4. For retaining the lever b'' in a normally forward position I provide a retracting-spring b^4 . To the free end of the lever b'' is pivoted a rack-gear bar C, the teeth c of which intermesh with a segment of gear-teeth c' , embracing the transverse crank-shaft D. This segmental gear c' is provided with a spring-actuated dog c^2 , adapted to engage notches $d d$, cut in the crank-shaft D. Secured in the body of the hand B there is also a spring-actuated dog D^3 , adapted to engage notches d' (see Fig. 3) on the crank-shaft D on the opposite side of the segmental gear c' , so as to prevent any backward rotation of the shaft D, these notches d' being so placed on the periphery of the crank-shaft D as to retain the cranks thereon slightly off of the center of the shaft, thereby causing a strain to be kept at all times upon the dog D^3 when the shaft is not in a state of rotation. The crank-shaft D is provided with four cranks D' , upon which are mounted pitmen D^2 , which extend to and are connected with the portions E of the fingers of the artificial hand by means of pivots e , as shown in Fig. 5 and by dotted lines in Fig. 4. The portions E of the fingers are pivoted to the body B of the hand by means of pivots e' . (See Fig. 5.) Mounted also upon the pivots e' are angle-arms F, one end, f , of which is fixedly secured to the body B of the hand and the other end, f' , extending upward in a chamber in the portion E of the fingers. Pivoted to the end f' of these angle-arms F in the portions E of the fingers are links f'' , (one of them being shown in Fig. 5,) the opposite ends of these links f'' being pivoted to the portions G of the fingers by means of pivots g .

H represents the wrist in the various figures, B the body of the hand, and E the fingers, and the finger portion G at 14 are cham-

bered out to receive the mechanism hereinbefore described and to allow of the free and unobstructed operation thereof.

To the body portion B of the hand there is 5 pivoted a thumb I by means of the pivot i, the inner end of this thumb being chambered out at 15 to allow space for the operation of a retracting-spring I', and the body B of the hand is also chambered out at 16 for the reception and operation of the spring I'.

The wrist-joint J is provided with notches j, which are engaged by a spring latch or stop j², by means of which the hand can be adjusted to a required angle and retained in that 15 position as long as desired. I also provide in the wrist portion a swivel-joint K, which is constructed as follows, viz: Upon the upper end of the wrist portion H, I secure a plate k, having a screw-threaded nipple K² upon the 20 central portion thereof, through the central portion of which nipple the chamber 2 extends to admit of the passage of the link b' therethrough. Upon the portion A' of the artificial arm which in order to secure lightness is 25 made hollow, as at A² in Fig. 4, I secure another plate, L, having a central opening therein of sufficient diameter to admit the screw-threaded nipple K² on the plate k to pass therethrough. Upon the screw-threaded end 30 of the nipple K², extending through the hole in the plate L, I secure an internally-screw-threaded collar K³, which holds the nipple K² within the opening in the plate L and the plate k, with the wrist portion H secured there- 35 to firmly against the plate L, but permits of the free rotation of the same upon the nipple in the arm portion A'. To secure the artificial hand at the desired point of rotation, I provide a number of notches or holes l in the 40 plate L, and in the wrist portion H, I secure a spring-actuated latch or stop h, which passes through an opening in the plate k and enters one of the notches or holes l in the plate L, thereby holding the hand portion in the de- 45 sired position.

I also desire to call attention to the construction of the wrist and finger joints of my improved artificial hand, which are of hinged-socket form, as shown in full and dotted lines 50 in Figs. 3, 4, and 5. Referring to Fig. 3, it will be seen that portions of a socket, M M, are milled out of the hand portion B at the wrist-joint J, which socket-chambers M M are adapted to receive portions N N of the hinge, formed 55 on the wrist portion H, and the wrist portion H is milled out to form portions M' M' M' of a socket, which socket portions are adapted to receive the portions N' N' N' of the hinge on the outside of and between the chambers M M 60 of the socket on the hand portion B, and through all of these overlapping hinge portions N N and N' N' N' a pivot m passes to secure the joint from being drawn apart. In the wrist-joint this pivot m is cut apart or a 65 portion thereof is cut away in the central part

thereof to admit of the free passage of the link b' through the wrist-joint. The finger and knuckle joints are similar in construction to the wrist-joint, except that there are fewer leaves or laps therein and the pivots therein 70 may be continuous therethrough. It will readily be seen that this form of joint presents no shoulders or projections upon its outside surface, which is a very desirable feature in artificial hands.

In operation when it is desired to close the fingers of the hand the wearer causes tension to be applied to the cord b and link b' ordinarily by a movement of the shoulder to which the artificial arm is secured, which draws the 80 lever b² and rack-gear bar C, secured thereto, back into the position shown by dotted lines in Fig. 4. This movement of the rack-gear bar C causes the segmental gear c' to turn, and the spring-actuated dog c² thereon engaging 85 one of the notches d in the crank-shaft D carries the crank-shaft D around one-half of a revolution, at which point the spring-actuated dog D² engages one of the notches d' in the 90 crank-shaft D on the side of the segmental gear opposite the spring-dog c² and holds it from turning backward when the tension is removed from the cord b and link b', when the retracting-spring b³ in the chamber 4 causes the lever b² and rack-gear bar C and segmental gear 95 c' to return to their normal positions. (Shown in full lines in Fig. 4.) The crank-shaft D, however, has been turned around one-half of a revolution and is held there by the spring-actuated dog D³, with the cranks D' thereof slightly off 100 of the center in order to maintain a strain upon the dog D³, which movement has changed the cranks D' and pitmen D² from the positions thereof shown in dotted lines in Fig. 4 to the position thereof shown by full lines in Fig. 5, 105 which movement of the pitmen D² draws the finger portions E and G from the positions thereof shown in Fig. 4 to that shown in Fig. 5. The fingers of this artificial hand are thus moved by the cord b and mechanism operated 110 thereby from a straight or open position to a closed position, and any object about which they are thus closed will be pressed against the thumb and will be tightly compressed therein by the action of the retracting-spring I upon 115 the thumb I, and said fingers will be retained in such closed position until tension is again applied to the cord b and link b', which will again move the lever b² and rack-gear bar C as before, and thereby cause the crank-shaft D 120 to complete its revolution, thereby carrying the cranks D' and pitmen D² back to the position shown by dotted lines in Fig. 4.

Having thus fully described my invention, so as to enable others skilled in the art to construct and utilize the same, what I claim as new, and desire to secure by Letters Patent of the United States, is—

1. The combination in an artificial arm, of an artificial hand secured thereto, swivel and 130

hinged joints intermediate of the elbow-joint and the artificial hand, fingers hinged thereto, mechanism in said artificial hand adapted to open and close the fingers thereof, a thumb member pivoted to the hand-body, and means for yieldingly holding said thumb member in a normally closed position in opposition to the fingers, substantially as and for the purpose set forth.

2. The combination in an artificial hand, of fingers hinged thereto, a transverse crank-shaft mounted in a chamber in the hand-body, a gear-wheel mounted on said crank-shaft, spring-actuated dog mechanism mounted on said gear-wheel and engaging notches in the periphery of said crank-shaft, a rack-gear bar engaging the gear-wheel on the crank-shaft, lever-and-link mechanism pivoted to said hand-body and to the rack-gear bar, spring mechanism for retaining said lever-and-link mechanism in a normally forward position, a spring-actuated dog secured to said hand-body and engaging notches in the periphery of the crank-shaft, pitmen pivoted to the cranks on said crank-shaft at one end and to the fingers of the hand at the other end thereof, substantially as and for the purpose set forth.

3. The combination in an artificial hand, of a transverse crank-shaft in the hand-body, mechanism adapted to rotate said crank-shaft a half-revolution, spring mechanism for retaining said mechanism in a normally outward

position, pitmen connecting the cranks on said crank-shaft with the lower portions of the knuckle-joints of the fingers on said hand, angle-arms mounted on the pivots of said knuckle-joints one end thereof being secured in the hand-body, links attached to the opposite ends of said angle-arms and to the lower part of the middle joints of the fingers, substantially as and for the purpose set forth.

4. In an artificial arm and hand, the combination of a swivel-joint in one part of the wrist portion, latch or stop mechanism adapted to secure said swivel-joint in a position desired, a hinged socket-joint in the wrist portion of said artificial hand below said swivel-joint, latch or stop mechanism for retaining said hinged socket-joint in a desired position, a hand-body, mechanism therein for opening and closing the fingers of said hand, fingers pivoted to said hand-body by means of hinged socket-joints, and means for connecting the actuating mechanism of the fingers with the body of the wearer whereby the same may be operated, substantially as and for the purpose set forth.

In testimony whereof I affix my signature in presence of two witnesses.

WILLIAM T. CARNES.
